UNITED STATES PATENT OFFICE.

WILLIAM B. C. HERSHHEY, OF COLUMBUS, OHIO.

DESIGN FOR A VEHICLE-SEAT HANDHOLD.

SPECIFICATION forming part of Design No. 34,866, dated July 30, 1901.

Application filed July 21, 1900. Serial No. 24,450. Term of patent 3½ years.

To all whom it may concern:

Be it known that I, WILLIAM B. C. HERSHHEY, a citizen of the United States, residing at Columbus, in the county of Franklin and State 5 of Ohio, have invented and produced a new and original Design for Vehicle-Seat Handholds, of which the following is a specification, reference being had to the accompanying drawings, forming part thereof.

Figure 1 is a view in perspective of my newly-designed handhold, and Fig. 2 is a front elevation of a handhold embodying said design.

Similar letters refer to similar parts throughout both views.

As shown in the drawings, the leading or material feature of my design consists in the handhold bar or body *a*, which inclines out-

wardly from its base to its head, describing a compound curve and terminating in its upper portion in an elongated curved and outwardly-projecting loop *b*. From the inner and upper portion of the loop projects rearwardly a short horizontal attaching-bar *c*, and from the lower end of the body *a* extends 25 inwardly a horizontal attaching-foot *d*.

Having described my invention, what I claim as new, and desire to secure by Letters Patent, is—

The design for a vehicle-seat handhold as 30 herein shown and described.

WILLIAM B. C. HERSHHEY.

In presence of—

C. C. SHEPHERD,
P. S. KARSHNER.
